UNITED STATES PATENT OFFICE.

JOSEPH B. SARGENT, OF NEW HAVEN, CONNECTICUT.

DESIGN FOR A BIRD-CAGE HOOK.

Specification forming part of Design No. 5,262, dated September 12, 1871.

To all whom it may concern:

Be it known that I, JOSEPH B. SARGENT, of the city and county of New Haven and State of Connecticut, have invented a new and original Design for Bird-Cage Hook; and I do hereby declare the following, when taken in connection with the accompanying drawing and the letters of reference marked thereon, to be a full, clear, and exact description of the same, and which said drawing constitutes part of this specification and represents a side view.

This invention relates to a design for a bracket-hook commonly known as bird-cage hook; and consists in the configuration of the arm, as shown and hereinafter described.

The screw and hook end are or may be of any desired form or construction. The arm between the two extremes is formed by an upper and lower bar filled in with lattice-work, as shown in the drawing. This peculiar formation of the arm constitutes my design.

I claim—

The design for bird-cage hook, as shown in the accompanying illustration and described.

J. B. SARGENT.
